UNITED STATES PATENT OFFICE

133,450

DESIGN FOR A COMBINED WASHING MACHINE AND WRINGER

Peter Eduard Geldhof, St. Joseph, Mich., assignor to Nineteen Hundred Corporation, St. Joseph, Mich., a corporation of Michigan

Application September 16, 1940, Serial No. 95,100

Term of patent 7 years

To all whom it may concern:

Be it known that I, Peter Eduard Geldhof, a citizen of the United States and a resident of the city of St. Joseph, in the county of Berrien and State of Michigan, have invented a new, original, and ornamental Design for a Combined Washing Machine and Wringer, of which the following is a specification, reference being had to the accompanying drawings forming a part thereof.

On the drawings:

Figure 1 is a perspective view of a combined washing machine and wringer showing my new design; and

Figure 2 is a top plan view thereof with the legs omitted for convenience of illustration.

The characteristic features of the design for the combined washing machine and wringer disclosed reside in the wringer having the specific configuration shown. The other side of the combination is substantially the same as the side shown, and the wringer supporting post is conventional.

I claim:

The ornamental design for a combined washing machine and wringer, as shown and described.

PETER EDUARD GELDHOF.
